WRITING IMPLEMENT

Hisanao Momma, 1188 Nunodi-machi, Chofu City,
Tokyo, Japan

Filed Dec. 14, 1964, Ser. No. 83,003

Claims priority, application Japan June 16, 1964

Term of patent 14 years

(Cl. D74—17)

Fig. 1.

Fig. 2.

Fig. 3.

Fig. 4.

Fig. 5.

Fig. 6.

FIG. 1 is a side view of a writing implement, showing my new design;

FIG. 2 is a side view thereof rotated 90 degrees from FIG. 1;

FIG. 3 is a side view rotated 180 degrees from FIG. 1;

FIG. 4 is an end view taken from the left of FIG. 1;

FIG. 5 is an end view taken from the right of FIG. 1;

FIG. 6 is a side view thereof as it appears with the cap omitted.

I claim:

The ornamental design for a writing implement, as shown.
